(57) **CLAIM**

The ornamental design for a pacifier, as shown and described.

DESCRIPTION

FIG. 1 is a perspective view of a pacifier showing my new design;

FIG. 2 is a top plan view of the pacifier of FIG. 1;
 FIG. 3 is a right side elevational view of the pacifier of FIG. 1, the left side elevational view being a mirror image of FIG. 3;
 FIG. 4 is a rear elevational view of the pacifier of FIG. 1; and,
 FIG. 5 is a front elevational view of the pacifier of FIG. 1.
 The broken lines illustrate environmental structure and form no part of the claimed design.**1 Claim, 1 Drawing Sheet**(56)
